(57) **CLAIM**

The ornamental design for a pod for use with a food or drink machine, substantially as shown and described.

DESCRIPTION

FIG. 1 is a top perspective view of a pod for use with a food or drink machine, showing my new design;

FIG. 2 is a bottom perspective view thereof;

FIG. 3 is a front elevation view thereof, the rear, right and left side elevation views being the same thereto;

FIG. 4 is a top plan view thereof; and,

FIG. 5 is a bottom plan view thereof.

The broken lines immediately adjacent the shaded areas represent the bounds of the claimed design while all other broken lines are included for the purpose of illustrating portions of the pod for use with a food or drink machine; the broken lines form no part of the claimed design.
